UNITED STATES PATENT OFFICE.

SAMUEL D. RUTH, OF BEATRICE, NEBRASKA.

INKING-PAD.

No. 872,754.

Specification of Letters Patent.

Patented Dec. 3, 1907.

Application filed February 20, 1907. Serial No. 358,492.

To all whom it may concern:

Be it known that I, SAMUEL D. RUTH, a citizen of the United States, residing at Beatrice, in the county of Gage and State of Nebraska, have invented a new and useful Inking-Pad, of which the following is a specification.

This invention relates to inking pads for hand stamps and the like and has for its object the provision of a comparatively simple and inexpensive device of this character in which the ink is fed upwardly through the pad and equally distributed over the surface thereof thus keeping the pad moist and preventing the latter from gumming or blurring.

A further object is to provide a perforated pad-supporting member having its lower face recessed to form an ink-receiving chamber which communicates with the ink reservoir and extends approximately the entire length of the pad, the ink in said chamber being fed upwardly through the perforations in the pad-supporting member.

A further object is to provide means for locking the pad against accidental displacement, and means for supplying ink to the reservoir.

A still further object of the invention is to generally improve this class of devices so as to increase their utility, durability and efficiency as well as to reduce the cost of manufacture.

With these and other objects in view the invention consists in the construction and novel combination and arrangement of parts hereinafter fully described, and illustrated in the accompanying drawings, it being understood that various changes in form, proportions and minor details of construction may be resorted to within the scope of the appended claims.

In the accompanying drawings forming a part of this specification: Figure 1 is a perspective view of an inking pad constructed in accordance with my invention. Fig. 2 is a longitudinal sectional view of the same. Fig. 3 is a transverse sectional view taken on the line 3-3 of Fig. 2 and looking in the direction of the arrow. Fig. 4 is a longitudinal sectional view of a portion of a pad illustrating a modified form of the invention.

Similar numerals of reference indicate corresponding parts in all of the figures of the drawings.

55 The improved inking pad forming the subject matter of the present invention includes

a substantially rectangular receptacle having a flat base 5 and parallel side walls 6 to one of which is pivotally connected a movable cover or closure 7. The end wall 8 of the receptacle is extended inwardly in parallel relation to the base 5 and thence downwardly for attachment to said base to form an ink reservoir 9, there being a longitudinal recess or discharge opening 10 formed in the vertical wall 11 of the reservoir and through which the ink in said reservoir is discharged into the bottom of the receptacle. Resting on the base 5 is a pad-supporting member 12 having its lower face provided with a longitudinal groove or recess forming a chamber 13 adapted to receive the ink in the reservoir 9, there being one or more perforations 14 formed in the supporting member so that the ink from the chamber 13 may be fed upwardly through said perforations and uniformly distributed over the surface of the pad 15. The upper end of the wall 11 is extended laterally to form an inclined shoulder 16 which bears against the adjacent surface of the pad 15 and which in connection with the inwardly extending flange 17 on the end wall 18 of the receptacle serves to effectively lock the pad against accidental displacement.

Pivottally mounted for lateral movement on the top of the ink reservoir 9 is a spring pressed arm 19 having its free end provided with a depending pad 20 which normally closes the feed-opening 21 formed in the reservoir 9, as shown, so that by moving the arm 19 laterally to inoperative position the ink may be introduced in the reservoir from whence it will flow through the opening 10 into the chamber 13. The groove or chamber 13 opens through one end of the pad-supporting member 12 while the opposite end of said member is provided with a transverse shoulder 22 so as to prevent the ink in the chamber 13 from escaping between the pad-supporting member and the adjacent end wall 18 of the receptacle.

It will here be observed that the marginal flange 23 of the pad-supporting member formed by the chamber 13 bears against the flat unobstructed base of the receptacle 5 and serves to confine the ink within the chamber 13 and thus prevent the latter from escaping at the longitudinal and transverse edges of the pad. The wall 8 of the receptacle is preferably bent inwardly at 24 to correspond with the flange 17 so that the cover

7 may be swung downwardly and entirely house the pad and its associated parts when the device is not in use. It will thus be seen that when the ink is introduced in the reservoir 9 the latter will flow through the recess 10 into the chamber 13 and will be supplied through the perforations 14 to the pad as needed.

In Fig. 4 of the drawings there is illustrated a modified form of the invention in which the arm 19 is dispensed with, the upper wall of the reservoir 9' being provided with a threaded opening 25 for the reception of a threaded plug or closure 26. It will of course be understood that the shoulder 16 on the vertical wall of the reservoir may be dispensed with and that either form of closure for said reservoir may be used at will.

Having thus described the invention what is claimed is:

1. An inking pad including a base, a perforated pad-supporting member resting on the base and having its lower face formed with an ink-receiving chamber, one end of the base being extended upwardly and thence inwardly and downwardly to form an ink-reservoir communicating with said chamber, and a pad resting on the supporting member and normally closing the perforations therein.

2. An inking pad including a receptacle, a perforated pad-supporting member disposed within the receptacle and having its lower face provided with a longitudinal ink-receiving groove defining a marginal flange adapted to bear against the base of the receptacle, one of the end walls of the receptacle being extended inwardly and thence extended downwardly to form an ink reservoir communicating with the groove, a pad engaging the supporting member and covering the perforations therein, and means for locking the pad against accidental displacement.

3. An inking pad including a receptacle having a flat base and one of its end walls extended inwardly and downwardly in spaced relation to the base to form an ink reservoir, there being an opening formed in the top of

the reservoir, a perforated pad-supporting member disposed within the receptacle and having its lower face formed with a longitudinal groove communicating with the reservoir, a pad covering the perforations in said supporting member, one wall of the reservoir being bent laterally to form a shoulder for engagement with the pad, and a closure for the opening in the reservoir.

4. An inking pad including a receptacle having one of its end walls extended inwardly and thence downwardly to form an ink-reservoir, there being a depression formed in one wall of the reservoir and a laterally extending shoulder formed on the opposite wall of said reservoir, a perforated pad supporting member disposed within the reservoir and provided with a longitudinal ink-receiving chamber communicating with the reservoir, a pad engaging the lateral shoulder of the ink-reservoir, a flange formed on one of the end walls of the receptacle and bearing against the pad, and a cover pivotally mounted on the receptacle and adapted to engage the depression and flange when the cover is moved to closed position.

5. An inking pad including a receptacle having one of its end walls extended inwardly and thence downwardly to form an ink-reservoir, a perforated pad supporting member disposed within the receptacle and having a longitudinal ink-receiving groove formed in the bottom thereof and opening through one end of said member, the opposite end of the groove terminating in a shoulder, a pad engaging the supporting member and covering the perforations therein, there being a feed-opening formed in the reservoir and communicating with the open end of the ink-receiving groove.

In testimony that I claim the foregoing as my own, I have hereto affixed my signature in the presence of two witnesses.

SAMUEL D. RUTH.
